(57) **CLAIM**

The ornamental design for a loud speaker cabinet, as shown and described.

DESCRIPTION

FIG. 1 is a perspective view of a loudspeaker cabinet showing our new design;

FIG. 2 is a front elevational view thereof;

FIG. 3 is a top plan view thereof;

FIG. 4 is a side elevational view taken from the left side of FIG. 2;

FIG. 5 is a rear elevational view thereof; and,

FIG. 6 is a bottom plan view thereof.

The broken line showing on FIGS. 1-6 is for illustrative purposes only and forms no part of the claimed design.
